UNITED STATES PATENT OFFICE.

CHARLES BLOSSOM, OF CELINA, OHIO.

BOX-LID HOLDER.

1,185,870.

Specification of Letters Patent. Patented June 6, 1916.

Application filed August 18, 1914. Serial No. 857,378.

To all whom it may concern:

Be it known that I, CHARLES BLOSSOM, citizen of the United States, residing at Celina, in the county of Mercer and State 5 of Ohio, have invented certain new and useful Improvements in Box-Lid Holders, of which the following is a specification.

This invention relates to box lid holders and has as its object to provide a device 10 simple in construction and adapted to be readily applied to a cigar box and arranged to hold the lid of the box in upright position.

It is one aim of the invention to so construct the holding device that it will not be liable to injure the cigars contained within the box and will not in any way obstruct or conceal the label upon the inner side of the box lid.

20 Another aim of the invention is to provide a holding device of the class described which may be manufactured at a low cost and in large quantities and which will consist of a single piece of material.

25 In the accompanying drawings: Figure 1 is a perspective view of the device applied to a cigar box and its lid. Fig. 2 is a perspective view of the device removed. Fig. 3 is a side elevation of the device applied. Fig. 4 is a front elevation illustrating a slightly modified form of the device. Fig. 5 is a perspective view of the form of the device shown in Fig. 4.

35 Corresponding and like parts are referred to in the following description and indicated in all the views of the accompanying drawings by the same reference characters.

In the drawings, the reference letter B indicates in general a cigar box and L the 40 lid thereof which is hinged to the rear wall of the box in the usual manner.

The lid supporting device embodying the present invention is here shown as formed from a single length of wire but, if desired, 45 any other suitable material may be employed.

The device embodying the present invention includes a shank portion which supports members to be engaged with the rear 50 wall of the box and with the lid. The device is formed from a suitable length of resilient wire, this length of wire being bent between its ends, as at 1, so as to form spaced portions 2 and 3 which comprise the shank of the device, the said portions extending parallel to each other and the por-

tion 2 being of less length than the said portion 3. At the upper end of the portion 2, the wire from which the device is formed is bent to extend forwardly at right angles, 60 as indicated by the numeral 4, and is thence bent downwardly, as at 5, to form a gripping finger located in advance of the said portion 2. The said portion 5, near its lower end and substantially at a point di- 65 rectly opposite the bend 1, is formed with a gradual bend 6 presented toward the said shank of the device. At the upper end of the portion 3, the wire is bent laterally to extend at right angles from the said por- 70 tion 3, as indicated by the numeral 7, this portion 7 being horizontally disposed and constituting one portion of the gripping member for the box lid. At the end of the portion 7, the wire is bent to extend rear- 75 wardly at right angles, as at 8, and is then bent to form a portion 9 which extends horizontally and parallel to the portion 7. The end of the portion 9 is bent, as at 10, to project toward the vertical plane occupied 80 by the shank portions 2 and 3 and occupies the same horizontal plane as the portions 7 and 9. The portions 2 and 3 comprising the shank of the device and the gripping finger 5, are so spaced that this part of the 85 device may be fitted over the upper edge of the rear wall of the box B with the portions 2 and 3 resting against the outer face of the said wall and with the finger 5 bearing at 90 its bend 6 against the inner face of the said wall. When the device is applied to the wall of the box, in the manner stated, the portion 4 will rest upon the upper edge of the said wall and the upper end of the portion 3 of the shank will project against the inner face of the box lid L, and that portion 95 of the device comprising the parts 7, 8 and 9, will engage about one lateral edge of the lid, the portion 7 bearing against the said inner face of the lid, the portion 8 bearing against the lateral edge of the lid, and the end of the portion 10 engaging against the rear or outer face of the lid. In that form 100 of the invention shown in Figs. 4 and 5 of the drawings, the structure is the same as 105 above described, except that the gripping finger 5 is bent in a direction the reverse of the bend 6, as indicated at 11, so that the lower end 12 of this finger may engage against the inner face of the rear wall of 110 the box.

From the foregoing description of the in-

vention, it will be seen that there is provided an extremely simple device of this character which may be readily applied to and removed from any ordinary cigar box 5 and which will not mar the appearance of the box and will hold the lid of the box in upright position so as to render the box attractive in appearance when placed within a show case or upon a counter.

10 Having thus described the invention, what is claimed as new is:

A box lid holder formed from a length of wire bent to provide parallel spaced portions occupying a common vertical plane 15 and constituting the shank of the holder to bear against the back of a box and the front of a lid thereon, the wire being extended forwardly from the upper end of one of said portions at an angle to the vertical 20 plane of the shank and then downwardly to

form a depending gripping finger disposed in co-operative relation to the shank, and the wire being extended laterally outward from the end of the other of said spaced portions across and in the plane of the shank to form a gripping portion and then bent rearwardly and then laterally inward to form a resilient gripping portion disposed in co-operative relation to and in the same horizontal plane with the said laterally extending gripping portion, the said resilient gripping portion and the depending gripping finger being bowed whereby to exert pressure toward the plane of the shank. 25

30 In testimony whereof I affix my signature in presence of two witnesses.

CHARLES BLOSSOM. [L. s.]
